Letters Patent No 676. Dated Oct 31 1854. Issued 13 Sep 1854

The schedule referred to in these Letters Patent and making part of the same
To all persons to whom these presents shall come

Be it known that I Nathaniel S Prince of Boston in the county of Suffolk and state of Massachusetts have invented or produced an ornamental Design for a Franklin Fire Place: which I do hereby declare is fully described in the accompanying drawings of which Figure 1. denotes a top view. Figure 2 a front elevation and Figure 3. a side elevation of said Fire Place. Figure 4 is a transverse vertical section of the side plate, cornice and a portion of the bottom plate the same being taken through the middle of said plate. Figure 5 is a transverse and vertical section of the front plate, the cornice and the hearth plate

This fire place is made with folding doors which are hinged to the body of the stove at the angles of the front and side plates and fold together in sections and around from the side plates to the front or over the grate

The grate which is seen at A. is flanked by paneled and ornamental pilasters which support an arched and paneled entablature the central panel being formed with a bust of Benjamin Franklin executed in "bass relief" on an elliptical shield. This bust is flanked by ornamental scroll work. Over the crown of the arch are the words "Villa Franklin"

The register plate as seen in Figure 1. bears the words, Franklin Stoggy and Co. Bangor. These words constitute a part of the ornamental design

Des 676

232

The ornaments of the top plate, the front, the side and the hearth plates are exhibited in the several figures and to the extent sufficient to enable a pattern maker skilled in the art of designing and constructing stoves or fire places of this description to clearly comprehend them

The front elevation shows one of the folding doors or parts of the blower as unfolded and extended over the front of the grate. This is composed of three sections hinged together each being paneled and ornamented. The other folding door or part of the blower is exhibited as partially folded or moved away from directly in front of the grate in order to represent the ornamental panel or pilaster which would be covered by the folding door while it is drawn around in front of the grate.

What is claimed by me is the ornamental design of the front of the fire place, also that of the folding blower; that of the top plate and that of the side, the same being as exhibited in the drawings
